HOUSING FOR A MOTORCYCLE SHOCK ABSORBER

Eugene J. Castelli, 148A Evendale Ave., Mountain View,
Calif. 94043; Ralph S. Miller, 10683 Minette Place,
Cupertino, Calif. 95014; and James M. Magee, 392
Firtree Court, Milpitas, Calif. 95035

Filed Sept. 9, 1974, Ser. No. 504,488

Term of patent 14 years

Int. Cl. D12—11
U.S. Cl. D12—159

FIG.1

FIG.2

FIG. 3

FIG. 4

FIG. 5

FIG. 1 is a side elevational view of a housing for a motorcycle shock absorber of our design, it being understood that the opposite side is a mirror image thereof;

FIG. 2 is a top plan view thereof;

FIG. 3 is an elevational view of one end thereof;

FIG. 4 is an elevational view of the opposite end thereof;

FIG. 5 is a bottom plan view thereof.

We claim:

The ornamental design for a housing for a motorcycle shock absorber, as shown.
